William J. Cook, Trumbull, Conn., assignor to General
Electric Company, a corporation of New York

Filed Mar. 30, 1966, Ser. No. 1,696

Term of patent 14 years

(Cl. D9—2)

Fig. 1.

Fig. 2.

FIG. 1 is a front perspective view of the vacuum cleaner embodying my new design;

FIG. 2 is a rear perspective view thereof; and

FIG. 3 is a side elevational view thereof.

The side not shown has substantially the same appearance as the side shown.

The top wall to which the handle of the vacuum cleaner is attached is substantially flat and plain.

I claim:

The ornamental design for a vacuum cleaner or similar article, substantially as shown and described.
